CLAIM

The ornamental design for a bag, as shown and described.

DESCRIPTION

FIG. 1 is a perspective view of a bag having a clear bottom and opaque sides.

FIG. 2 is a front elevation view thereof, the back view being a mirror image thereof.

FIG. 3 is a side elevation view thereof, the opposite side view being a mirror image.

FIG. 4 is a top plan view thereof; and,

FIG. 5 is a bottom plan view thereof.

In the drawings, the broken lines illustrate unclaimed features and form no part of the claim.
